United States Patent Office.

WILLIAM LA BANISTER AND CHARLES W. RICKER, OF CHARLESTOWN, MASSACHUSETTS, ASSIGNORS TO CHARLES W. RICKER AND SAMUEL S. WILSON, OF SAME PLACE.

Letters Patent No. 97,203, dated November 23, 1869.

IMPROVEMENT IN FLIERS FOR SPINNING.

The Schedule referred to in these Letters Patent and making part of the same.

To all whom it may concern:

Be it known that we, WILLIAM LA BANISTER and CHARLES W. RICKER, of Charlestown, in the county of Middlesex, and in the State of Massachusetts, have invented certain new and useful Improvements in Cotton-Spinning Fliers; and do hereby declare that the following is a full, clear, and exact description thereof, reference being had to the accompanying drawings, and to the letters of reference marked thereon, making a part of this specification.

The nature of our invention consists in a flier for cotton spinning, the legs of which are constructed as hereinafter described, and provided with projections, cast with them, to take the place of the guide-wire on the old flier.

In order to enable others skilled in the art to which our invention appertains, to make and use the same, we will now proceed to describe its construction and operation, referring to the annexed drawing, which represents a perspective view of our invention.

The general shape or outline of our cotton-spinning flier is the same as those now in use, A being the head, B, the foot, and C C, the parallel legs or uprights.

The legs or uprights C C are each cast in one piece, with a boss or projection, D, at about the centre, and on opposite sides of the flier, which projections are drilled and slotted, as shown, so as to form guides for the thread.

The simple guide-wire on the usual fliers often breaks the thread, and is often broken itself, by knots; but, in this case, the "boss" is not a wire, but a part of the upright, and, consequently, will not be broken so easily, nor will it break the thread.

Above the bosses or projections D D, the legs or uprights C C are oval or elliptical, and below the same they are semicircular, so as to strengthen the flier at the points where the greatest strain is upon it.

Owing to the great speed with which fliers are generally run, the uprights are very often thrown out of their normal position, or bent, thus shortening the flier. This is entirely obviated by making them in the form above described, as the air will not give so much resistance, the legs or uprights, so to say, cutting the air. For this reason, our flier can be run at about one-third more speed than usual. It is cheaper, and will make better work.

The flier thus constructed may be cast of malleable iron, or forged of either steel or iron, or cast of any metal, hardened or case-hardened.

Having thus fully described our invention,

What we claim as new, and desire to secure by Letters Patent, is—

The combination of the head A, foot B, uprights C C, and bosses or projections D D, when said projections are formed in one piece with the uprights, and said uprights are oval above, and semicircular below said projections, substantially as and for the purposes herein set forth.

In testimony that we claim the foregoing, we have hereunto set our hands and seals, this 6th day of September, 1869.
